SHIELD FOR ELECTRIC WALL SOCKETS

John N. Leopold, Staten Island, N. Y.

Application December 20, 1945, Serial No. 636,230

3 Claims. (Cl. 173—330)

1

This invention relates to new and useful improvements in a shield for an electric wall socket.

More specifically, the present invention proposes the construction of a shield adapted to cover electric circuit plugs in an electric wall socket so that they may not be tampered with by children or accidentally knocked out of place, the shield being characterized by having a semi-cylindrical body closed at its ends and preferably made of transparent plastic or similar material, the body having means for securing it to the plate of the wall socket and having orifices for the passage of the electric wires of the plugs.

A further object is to provide a shield as aforesaid having fastening means which can not be tampered with by children.

Another object is to provide a shield as aforesaid having special attachment to the wall socket.

Still another object is to provide a shield having flanges adapted to be gripped by the wall socket plate.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a shield constructed in accordance with the present invention, the shield being shown with the associated structure that it will be used with.

Fig. 2 is a sectional view on the line 2—2 of Fig. 1.

Fig. 3 is a perspective view of the shield alone.

Fig. 4 is a transverse sectional view similar to Fig. 2 but with certain parts omitted, showing a modification of the present invention.

Fig. 5 is a perspective view of a fitting shown in Fig. 4.

Fig. 6 is a perspective view of a special screw for attaching the shield to a wall socket.

Fig. 7 is a view of a tool to be used with the screw of Fig. 6.

Fig. 8 is a view similar to Fig. 1 showing a modification of this invention.

Fig. 9 is a sectional view on the line 9—9 of Fig. 8.

Fig. 10 is a view of the shield of Fig. 8 in open position.

This shield, according to the present invention, is adapted to cover the plugs 10 of electric cords 11, the plugs being plugged into the sockets 12 of a wall socket 13 having a plate 14 held in place

by a center screw, later to be described. The wall socket, plate and sockets are all conventional and are assembled with a box 15 in a hole 16 of a base board 17 of a room 18. Ordinarily the plate 14 is held in place by a small screw threaded into a threaded orifice in the bar that supports the sockets 12 in the box 15. However, according to the present invention, this customary screw is replaced by another screw, later to be described.

When wall sockets are left unprotected, they are a source of great interest to small children, who delight in pulling out the plugs, tampering with them, sticking hairpins and the like into the sockets and in general doing damaging and dangerous acts. The shield of the present invention, indicated generally by the reference number 19, is designed to prevent such malicious or mischievous acts. It also prevents accidental pulling of the plugs out of the sockets, which is important in the case of devices such as electric clocks which become inactive when unplugged.

The shield is preferably made of transparent plastic, although it may be made of other material if desired. It has a semi-cylindrical front wall 20 and integral side walls 21. At its center, it has a hole 22 and along one edge it has two recesses 23. A shouldered screw 24 secures the shield to the plate 14 and the plate 14 to the box. This screw 24 has a threaded end adapted to be screwed into the socket support in the usual manner. It also has a shoulder 25 adapted to engage the outer face of the plate 14. The shoulder must be smaller than the hole 22 so that it can pass therethrough and the head 26 of the screw must be larger than the shoulder 25 so that it can't pass through the hole 22. The inner edges of the shield are all in one plane so that they bear evenly against the base board, with the wires 11 extending through the recesses 23.

The shield is quite rigid due to the integral structure of the side and front walls. The screw, due to the shoulder, can be turned tightly in place so that children can not remove it. The transparency of the shield enables a person to inspect the plugs without removing the shield. The front wall of the shield lies close enough to the plugs and the wires therein to prevent the plugs from being pulled out of the sockets. The shield is fastened in place after the plugs are in the sockets, the plate 14 being in place but unfastened until the screw 24 is tightened home.

In Fig. 4 is a modified type of screw which may be employed if desired. Here a fitting 27 is employed for holding the plate 14 in place in the box. Thus the plate may be secure before the

shield 10' is fastened in place. The fitting has a shoulder 25' and a threaded socket 28 in which an ordinary bolt 29 is screwed to secure the shield to the plate.

In Fig. 6 a special bolt 29' is shown which may be used in place of the bolt 29. The head 30 of this bolt is not provided with a slot but is provided with two pits 31 which can be employed, by means of the tool 32 shown in Fig. 7, in turning the screw. However, a child not possessing the tool 32 can not turn this screw with an ordinary screw driver.

A shield 10" constructed in accordance with another modification of this invention is shown in Figs. 8-10. The shield is similar to the shield of Fig. 1 except that the side walls 21" are formed of two parts 21^a and 21^b divided at the seam 21^c permitting the top face 20" to be partly unrolled as shown in Fig. 10. Also, the top and bottom edges are provided with flanges 33.

The shield of Figs. 8-10 is adapted to be assembled with the wall socket as follows:

After the plugs 10" are in place, the screw 34, which is the usual screw employed in wall sockets, is loosened and the flanges 33 tucked in under the edges of the plate 14", the shield being opened to its position shown in Fig. 10 to enable the flanges 33 to be so tucked in. The screw 34 is then tightened up by a screw driver inserted through the hole 22", firmly locking the flanges 33 in place and preventing the shield from being removed.

The especial advantage of the shield of Figs. 8-10 is that it is tamper-proof. A child can not get at the screw 34 without a particular type of screw driver that would fit through hole 22".

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A shield for protecting electric cord plugs inserted in the sockets of a wall socket box comprising a semi-cylindrical body having end clos-

ing walls, each of said end walls being divided into two parts by an openable seam, the edges of said body perpendicular to said end walls terminating in flanges extending inwardly into said shield, said body having ports for the passage of said electric cords and a hole adapted to align with the screw hole of the plate of the wall socket box, said flanges being adapted to be caught under said plate.

- 10 2. A shield for protecting electric plugs inserted in the sockets of a wall socket box comprising a semi-cylindrical body having end closing walls, each of said end walls being divided into two parts by an openable seam, the edges of said body perpendicular to said end walls terminating in flanges extending inwardly into said shield, said body having ports for the passage of said electric cords, said flanges being adapted to be caught under a socket face plate.
- 15 3. A shield for the sockets of a wall socket box comprising a semi-cylindrical body having end closing walls, each of said end walls being divided into two parts by an openable seam, the edges of said body perpendicular to said end walls terminating in flanges extending inwardly into said shield, means affording passage of electric cords into said shield, and said flanges being adapted to be caught under a socket face plate.

JOHN N. LEOPOLD.
